UNITED STATES PATENT OFFICE.

JACOB J. BRAUN, OF NEW YORK, N. Y., ASSIGNOR TO EDWIN D. BELKNAP.

MACHINE FOR ADDRESSING ENVELOPS AND THE LIKE.

No. 823,988.

Specification of Letters Patent.

Patented June 19, 1906

Application filed August 8, 1905. Serial No. 273,225.

To all whom it may concern:

Be it known that I, JACOB J. BRAUN, a citizen of the United States, residing in the borough of Brooklyn, in the county of Kings, in the city and State of New York, have invented certain new and useful Improvements in Machines for Addressing Envelops and the Like, of which the following is a specification.

This invention relates to that class of machines wherein the address is stenciled on the envelop, wrapper, or the like from a stencil-card, which latter is fed into position and inked by a roller, the envelop or other thing upon which the matter is to be stenciled being held down by a movable platen.

The main object of the present invention is to simplify and cheapen the construction and to provide a means whereby the addressing may be duplicated. For example, means are provided whereby one address may be printed from each stencil-card, or two or more addresses may be printed therefrom successively, as desired, by arresting the feed.

In the accompanying drawings, which illustrate an embodiment of the invention, Figure 1 is a plan of the machine. Fig. 2 is a transverse vertical section thereof, taken at line x^2 in Fig. 1. Fig. 3 is a plan from which the machine-bed is omitted, so as to show the mechanism below it. Fig. 4 is a vertical section at line x^4 in Fig. 1. Figs. 5 and 6 are side elevations of the left-hand side of the machine, showing the movable parts in different positions. In these views the frame is partly broken away. Fig. 7 shows a stencil-card in cross-section on a larger scale than the principal views. Fig. 8 is a detail which will be hereinafter described.

In the principal views, T designates a table, in which the machine may be mounted for convenience of operation. This table or table-bed may be of wood.

1 is the bed and frame of the machine, provided with suitable lugs 2 or other means for securing it to the table.

3 is the delivery-hopper for holding the stencil-cards, and 4 is the receiving-hopper therefor.

In the machine-frame is mounted an ink-fountain 5, provided with a fountain-roller 6, and also in the frame is fulcrumed at a

lever 7, carrying on its upper arm a platen 8. In the frame and mounted in bearings in brackets 9 thereon is a rock-shaft 10, which has an arm 11, carrying a stud-roller 12, which plays in a cam groove or slot 13 in an operating-lever 14, fulcrumed at b on the frame. By rocking the lever 14 about its fulcrum the shaft 10 is rocked.

On the lever 14 is an arm 15, which is coupled by a link 16 to a bar or plate 17, mounted to slide forward and back on guides 18. This bar carries the feeders for the stencil-cards S, one of which is seen in section in Fig. 7. The feeders or pushers 19, preferably two, are preferably hinged at c in the sliding bar 17, and when in operative position a shoulder 19^a on the pusher engages the thick board frame s of the lower stencil-card in the hopper 3 and in the forward or feeding movement of the said bar carries or pushes the card forward in guides 20 on the bed of the machine to a point under the elevated platen 8, which serves to press the envelop down on the card and to back it while the stenciling of the address is being effected. The platen is operated by a cam 21 on the lever 14, which acts on an eccentric stud-roller 22, mounted in a pendent arm of the lever 7, which carries the platen. Fig. 8 is a detail sectional view showing the eccentric mounting of the stud-roller 22, the object of said mounting being to regulate the pressure of the platen on the envelop or sheet which receives the stenciled inscription from the card. A spring 23 retracts the platen.

An inking-roller 24 is rotatively mounted in a frame 25, and this frame is coupled at d to an arm 26 on the rock-shaft 10. This shaft moves the roller 24 from its contact with the fountain-roller 6, where it receives ink forward in the printing or stenciling movement and back again to its first position. In order to lift the inking-roller from the fountain-roller to the level required for applying ink to the stencil-card S that may at the time be in the proper position under the platen, the journals of said inking-roller rest on or engage track-cams 27 on the frame, Figs. 3, 4, and 5, and when the said roller is retracted these cams permit it to descend into contact again with the fountain-roller. In order to distribute the ink properly on the inking-roller 24, means are provided for rotating the fountain-

roller during the backward movement of the inking-roller and also while these two rollers are in contact.

On one projecting journal of the fountain-roller 6, (seen at the left in Fig. 2) is a ratchet-wheel 28, and on the other journal thereof is a spur-wheel 29. A spring-pawl rack 30, carried by the lever 14, engages the ratchet-wheel 28 and rotates the fountain-roller 5 when the lever 14 is actuated. A pawl-wheel 31 on one journal of the inking-roller 24 moves into gear with the spur-wheel 29, and thus is assured the rotation of the roller 24 in peripheral contact with the fountain-roller 10 and with the same peripheral speed. In order to compel the inking-roller 24 to rotate when it passes over the under surface of the stencil-card, the teeth of the spur-wheel 31 thereon are made to gear when the roller is lifted up by 15 the track-cams 27 with a fixed rack 31^a in or on the lower face of the machine-bed.

The card S is made in the usual way of a piece of hard thin paper, which has the stencil formed on it with perforating-types, and a 20 stiff frame s of paper-board or the like. The cards are superposed in the hopper 3 in the usual way, and the shoulders on the pushers 19 engage the frame of the lowermost card in the hopper and push it forward along the guides 20 to its position under the platen 8. In the operation the attendant places the envelop or whatever is to receive the stenciled inscription on the guides 20 and up to any suitable stops on the machine in proper position under 25 the platen, which latter descends and presses the envelop into close contact with the stencil-card. Then the roller 24, charged with ink, rises and moves forward, rolling over the lower face of the stencil and back again. The 30 platen then lifts, and the addressed envelop is removed. The next stencil-card brought forward displaces that one under the platen and pushes the latter into the receiving-hopper 4.

In the present drawings only the operating-lever 14 is shown adapted to be actuated by hand, for example; but it will be obvious that it may be operated by power through other means now well known. In case said lever is to be operated by other means than by 45 hand the power may be coupled to the lever at 32, Figs. 5 and 6.

It is desirable that the feeding of the stencil-cards shall be arrested in order to permit several envelops to be stenciled with the 50 same address, and in order to effect this the pushers 19 will be by preference pivotally connected or hinged to the plate or bar 17, so that they may be let down far enough to prevent them from engaging the lowermost card S in the hopper 3 during one or more stenciling operations, whereby the card at the time in position under the platen 8 may be employed to stencil two or more envelops. The devices employed for effecting this object are best

illustrated in Figs. 1, 3, and 4 and will now be described.

On a shaft 33, extending across the frame of the machine at the back, are two cams 34, disposed under the respective pushers 19 in position normally to uphold them and keep them 70 in the operative feeding position or plane. On the shaft 33 is a ratchet-wheel 35, having a stop-pawl 36 (see Fig. 4) to prevent back rotation. An operating spring-pawl 37 is carried by an arm 38, secured to an upright abutment 39, which rocks in a bearing in the machine-bed and has secured to its upper end a regulating-arm 40, Fig. 1, which has an aperture in its end to receive a pin 41, that may 75 secure the arm 40 in any one of several positions by engaging holes w, x, y, and z in the bed of the machine.

The operation is as follows: The ratchet-wheel 35 has (or may have) twelve teeth, and the cam 34 is double-ended, so that if from 80 the operative position (seen in Fig. 4) the cam is rotated half-way round its other end will lift the pusher into operative position. Now if the cam is in position to uphold the pusher and the regulating-arm 40 is set at the hole w 85 the pawl will not act, as it will be drawn back out of operative position. If the arm 40 be set at the hole x, then it will rotate the ratchet-wheel 35 to the extent of one tooth at each reciprocating movement of the pushers. If said arm 40 be set at the hole y, it 90 will cause the pawl to move the ratchet-wheel to the extent of two teeth at each feeding movement, and if set at the hole z the pawl will move the ratchet-wheel to the extent of three teeth at each feeding movement. Obviously when the cams are not in position to elevate the pushers into their feeding or 95 operative positions no cards will be fed from the hopper, and the same card will be employed at each stenciling operation.

The present invention is not restricted to two or more pushers and lifting-cams therefor. Two are preferred; but one broad pusher would serve, or the pushers might be rigidly 100 connected together and only one cam employed. These variations will be obvious to any skilled mechanic.

The inking-roller 24 may be a rubber-covered roller suitable for taking up and delivering 105 the ink properly to the stencil.

Having thus described my invention, I claim—

1. A machine for the purpose specified, having an ink-fountain and fountain-roller, 110 an inking-roller, cams which support the journals of said inking-roller, a frame in which said roller is carried, means for feeding stencil-cards into position to be inked by said roller, a movable platen, a lever carrying 115 said platen, a rock-shaft having an arm coupled to the frame carrying the inking-roller and another arm carrying a stud-roller, an

operating-arm, having a cam-slot engaged by said stud-roller for rocking said shaft, and having also a cam for operatively actuating the platen, and a spring for retracting the platen.

2. A machine for the purpose specified, having an ink-fountain and fountain-roller, said roller being provided on one journal with a hatchet-wheel and on the other journal with a spur-wheel, an operating-lever provided with a spring-pawl engaging said ratchet-wheel, a reciprocating frame, an inking-roller carried by said frame and adapted to be moved into and out of contact with the fountain-roller by reciprocation of said frame, a spur-wheel on the journal of the inking-roller, adapted to gear with the spur-wheel carried by the fountain-roller, a reciprocating platen, and means for feeding stencil-cards to a position under said platen.

3. A machine for the purpose specified, having reciprocating devices for feeding a stencil-card to the stenciling position, a reciprocating platen, means for inking the stencil-card, and means for intermitting the feed of the stencil-cards in order to effect a plurality of stenculings from a single card, said means comprising automatic mechanism for lowering the feeding device into an inoperative plane.

4. In a machine for the purpose specified, the combination with a reciprocating platen, and means for applying ink to the stencil-card, of means for feeding the cards to the stenciling-point, said means comprising a reciprocating bar, a pusher for the card, mounted pivotally on said bar, a shaft 33, rotatively mounted in bearings on said bar, a supporting-cam 34 on said shaft under said pusher, a ratchet-wheel 35 on said shaft, and an adjustable pawl 37, adapted to engage said ratchet-wheel when set for operation.

5. In a machine for the purpose specified, the combination with a reciprocating platen, a reciprocating roller below said platen for applying ink to the stencil-card, and means for feeding the cards to the stenciling-point, consisting of a pusher carried by a reciprocating bar, of a device for intermitting the feeding of the cards, said device consisting of automatic means for lowering the pusher into an inoperative plane and raising it into the operative plane, alternately, as set forth.

In witness whereof I have hereunto signed my name, this 4th day of August, 1905, in the presence of two subscribing witnesses.

JACOB J. BRAUN.
